UNITED STATES PATENT OFFICE.

VERNER J. WAHLSTROM, OF BROOKLYN, NEW YORK, ASSIGNOR TO AMERICAN MACHINE AND FOUNDRY COMPANY, A CORPORATION OF NEW JERSEY.

TOBACCO CUTTER.

Application filed May 22, 1924. Serial No. 714,997.

To all whom it may concern:

Be it known that I, VERNER J. WAHLSTROM, a citizen of the United States, residing at Brooklyn, county of Kings, and 5 State of New York, have invented a new and useful Improvement in Tobacco Cutters, of which the following is a specification.

This invention relates to an improvement 10 in tobacco cutters for shredding tobacco for cigarette manufacture; and its main object is the production of an efficient and economical machine of this type in which the feeding means is controlled directly by the means 15 employed for shredding the tobacco. With this and other objects not specifically mentioned in view, the invention consists in certain constructions and combinations which will be hereinafter fully described and then 20 specifically set forth in the claims hereunto appended.

In the accompanying drawings, which form a part of this specification and in which like characters of reference indicate 25 the same or like parts, Fig. 1 is a front elevation of a cutter constructed in accordance with the invention, Fig. 2 is a sectional view taken on the line 2—2 in Fig. 1, and Fig. 3 is a plan viewed from the line 3—3 in 30 Fig. 1.

In carrying the invention into effect, there is provided means for feeding the tobacco in a thick mass or sheet, means for slicing the sheet as fed to form shreds of tobacco, 35 and cam-controlled means for intermittently operating the feeding means while the shredding means is not cutting. In the best constructions contemplated, the operating means includes a ratchet mechanism 40 actuated by the knife-carrying frame of the shredding means while said frame is moving upwardly after a cut has been effected, and worm-wheel mechanism actuated intermittently by the ratchet mechanism for rotating the feed rollers. The above mentioned means and mechanism may be widely 45 varied in construction within the scope of the claims, for the particular machine selected to illustrate the invention is but one

of many possible concrete embodiments of 50 the same. The invention, therefore, is not to be restricted to the precise details of the structure shown and described.

In the machine selected to illustrate the invention, 4 indicates the machine frame, 55 and 5 indicates the bottom of a trough, and 6 its sides, in which the machine operator builds up a thick sheet of tobacco. At one end of this trough are two superposed feed 60 rollers 7 and 8 having corrugated peripheries for dragging the sheet of tobacco along the bottom of the trough and forcing it in compressed condition through a throat 9 just beyond said rollers. The roller 7 is fast on and driven by a shaft 10, and the 65 roller 8 is fast on and driven by a shaft 11, both of these shafts being journaled in suitable bearings supported by the machine frame. The shaft 10 carries and is driven by a worm-wheel 12, and the shaft 11 carries 70 and is driven by a worm-wheel 13. Both worm-wheels are in mesh with a vertical shaft 14 having a right-hand worm 15 driving the worm-wheel 12, and a left-hand worm 16 driving the worm-wheel 13. The 75 means employed for operating this vertical shaft will be hereinafter described.

At the end of the throat 9 is located a shear plate 17 secured to the machine frame. 80 Coacting with this shear plate is a reciprocating knife 18, secured to a knife-carrying frame 19 by means of clamp bolts 20 and adjusting screws 21. The knife-carrying frame 19 is slidably mounted between gibs 22, 22 secured to the machine frame. 85 It is reciprocated by means of a yoke 23 pivoted to a bar 24 fast in bosses 25, 25 formed on the frame 19. The other end of this yoke is journaled on a crank 26 formed on the power shaft 27 journaled in bearings 90 28, 28 on the machine frame. This shaft is driven by means of a belt, not shown, but operating on the fast and loose pulleys 29 and 30. The shaft 27 also carries a balancing fly-wheel 31. By means of the mechanism just described, the knife is moved 95 upwardly and downwardly across the throat 9 through which the tobacco pro-

trudes as fed about $\frac{1}{16}$ of an inch during each cycle of operations. The tobacco sliced off is in the form of long shreds suitable for cigarette manufacture.

5 The means employed for operating the feeding means in accurate timed relation with the movement of the knife 18 includes a ratchet mechanism actuated by the knife-carrying frame 19 of the shredding means. 10 With this end in view, a ratchet 32 is fast on the upper end of the vertical shaft 14 before referred to. Just below this ratchet, and rotatably mounted on the shaft 14, is an oscillating member 33 carrying a pawl 34 engaging the ratchet. This oscillating member is provided with a spiral groove 35, and in this groove is a roller 36 carried by the knife-carrying frame 19. A detent pawl 37, supported by the machine frame, also engages the ratchet.

20 When the knife-carrying frame is moved downwardly to shred the tobacco, the roller 36 moves downwardly in a straight line, and in so moving causes the oscillating member 25 33 to rotate on the vertical shaft 14, bringing the pawl 34 back with it for a fresh bite on the ratchet. Then, on the return or 30 upward stroke of the knife-carrying frame, it is time for the feeding means to operate 35 to advance the sheet of tobacco another $\frac{1}{16}$ of an inch, and so, during this upward movement of the knife-carrying frame, the oscillating member is rotated in the opposite direction and the pawl 34 rotates the ratchet 32 and the shaft 14 fast thereto, thus operating the worm-wheel mechanism and feed rollers 7 and 8. The cycle of operations is then repeated.

What is claimed is:

40 1. A tobacco shredder comprising means for feeding a sheet of tobacco, means for shredding said sheet as fed, and cam-controlled means actuated by said shredding means for intermittently operating said feeding means.

45 2. A tobacco shredder comprising means for feeding a sheet of tobacco, means for shredding said sheet as fed, and cam-controlled means actuated by said shredding means for intermittently operating said feeding means, said operating means including a ratchet mechanism actuated by a reciprocating part of said shredding means.

50 3. A tobacco shredder comprising means for feeding a sheet of tobacco, means for shredding said sheet as fed, and cam-controlled means actuated by said shredding means for intermittently operating said feeding means, said operating means including a ratchet mechanism actuated by the knife-carrying frame of said shredding means.

55 4. A tobacco shredder comprising means for feeding a sheet of tobacco, means for shredding said sheet, as fed, and cam-con-

trolled means actuated by said shredding means for intermittently operating said feeding means, said operating means including a ratchet mechanism having an oscillating member provided with a spiral groove 70 engaging the knife-carrying frame of said shredding means.

5. A tobacco shredder comprising means for feeding a sheet of tobacco, means for shredding said sheet as fed, and cam-controlled means actuated by said shredding means for intermittently operating said feeding means, said operating means including a ratchet mechanism engaged by the knife-carrying frame of said shredding means, and worm-wheel mechanism 75 intermittently operated by said ratchet mechanism.

6. A tobacco shredder comprising means for feeding a sheet of tobacco, means for shredding said sheet as fed, and cam-controlled means actuated by said shredding means for intermittently operating said feeding means, said operating means including a vertical shaft, and ratchet mechanism 80 mounted on and intermittently rotating 85 said shaft.

7. A tobacco shredder comprising means for feeding a sheet of tobacco, means for shredding said sheet as fed, and cam-controlled means actuated by said shredding means for intermittently operating said feeding means, said operating means including a vertical shaft, and ratchet mechanism 90 mounted on and intermittently rotating 95 said shaft and provided with an oscillating member having a spiral groove 100 engaged by the knife-carrying frame of said shredding means.

8. A tobacco shredder comprising means for feeding a sheet of tobacco, means for shredding said sheet as fed, and cam-controlled means actuated by said shredding means for intermittently operating said feeding means, said operating means including a vertical shaft, a ratchet fast on 105 said shaft, an oscillating member actuated by said shredding means, and a pawl carried by said member and engaging said ratchet.

9. A tobacco shredder comprising means for feeding a sheet of tobacco, means for shredding said sheet as fed, and cam-controlled means actuated by said shredding means for intermittently operating said feeding means, said operating means including a vertical shaft, a ratchet fast on 110 said shaft, an oscillating member engaged and actuated by a reciprocating part of said shredding means, and a pawl carried by 115 said member and engaging said ratchet.

10. A tobacco shredder comprising means for feeding a sheet of tobacco, means for shredding said sheet as fed, and cam-controlled means actuated by said shredding 120 125 130 means.

means for intermittently operating said feeding means, said operating means including a vertical shaft having right and left hand worms thereon, right and left hand worm-wheels driven by said worms, feed rollers rotated by said worm-wheels, a ratchet fast on said shaft, an oscillating member rotatable on said shaft and actuated by said shredding means, and a pawl carried by said member and engaging said ratchet.

In testimony whereof, I have signed my name to this specification.

VERNER J. WAHLSTROM.
